FIG. 1

FIG. 2

FIG. 3

FIG. 1 is a front perspective view of a wrap-around tail light showing my new design;

FIG. 2 is a rear elevational view thereof; and

FIG. 3 is a left side elevational view thereof.

The cross hatching in FIG. 1 indicates conventional reflective faceting. The cross hatching is partially shown on the front and side for convenience of illustration, it being understood to be uniformly continuous over the areas indicated.

I claim:

The ornamental design for a wrap-around tail light, as shown and described,
